UNITED STATES PATENT OFFICE

104,540

DESIGN FOR AN ENSEMBLE DRESS

Jack Greenman, New York, N. Y.

Application March 8, 1937, Serial No. 68,075

Term of patent 3½ years

To all whom it may concern:

Be it known that I, Jack Greenman, a citizen of the United States, residing in the county of Kings, city and State of New York, have invented a new, original, and ornamental Design for an Ensemble Dress, of which the following is a specification, reference being had to the accompanying drawing constituting a part thereof:

The characteristic feature of the design resides in the skirt of the ensemble, which skirt is decorated as shown.

I claim:

The ornamental design for an ensemble dress substantially as shown and described.

JACK GREENMAN.
